US0D1054035S

(12) **United States Design Patent** (10) Patent No.: **US D1,054,035 S**
(45) Date of Patent: ** Dec. 10, 2024

(54) **IMAGING SYSTEM**

(71) Applicant: **Hologic, Inc.**, Marlborough, MA (US)

(72) Inventors: **Timothy N. Wells**, Manchester, CT (US); **Thomas Farbizio**, Newton, CT (US); **Kenneth F. DeFreitas**, Patterson, NY (US); **John Girgenti**, New Milford, CT (US); **Caroline Cowles**, Ridgefield, CT (US); **Erwin Sahagun**, Shelton, CT (US); **Philip D. Palermo**, Marietta, GA (US); **Benjamin Bailey**, Clarkston, GA (US); **William Daniel Borzon**, Stanford, CA (US)

(73) Assignee: **Hologic, Inc.**, Marlborough, MA (US)

(**) Term: **15 Years**

(21) Appl. No.: **29/854,690**

(22) Filed: **Sep. 27, 2022**

Related U.S. Application Data

(63) Continuation of application No. 17/278,973, filed as application No. PCT/US2019/052721 on Sep. 24, 2019.

(57) **CLAIM**

The ornamental design for an imaging system as shown and described.

DESCRIPTION

The sole FIGURE is a perspective view of the imaging system.

The portions depicted in broken lines form no part of the claimed design.

1 Claim, 1 Drawing Sheet
